UNITED STATES PATENT OFFICE.

JOSEPH D. GILLAN, OF PROVIDENCE, RHODE ISLAND, ASSIGNOR OF ONE-HALF TO
JOHN F. BRADY, OF PROVIDENCE, RHODE ISLAND.

FASTENER.

1,199,690.

Specification of Letters Patent. Patented Sept. 26, 1916.

Application filed March 9, 1915. Serial No. 13,119.

To all whom it may concern:

Be it known that I, JOSEPH D. GILLAN, a citizen of the United States, residing at Providence, in the county of Providence and State of Rhode Island, have invented 5 certain new and useful Improvements in Fasteners, of which the following is a specification.

My invention relates to fasteners for 10 chains, filaments, or other articles and devices.

The essential objects of my invention are to prevent accidental disengagement of the fastening parts, and the attainment of this 15 purpose in a structure simple to operate and inexpensive to construct.

To the above ends essentially my invention consists in such parts and combinations of parts as fall within the scope of the 20 appended claims.

In the accompanying drawings which are 25 a part of this specification, and in which is shown merely a preferred form of embodiment of my invention, Figure 1 is a side elevation of my fastener, Figs. 2 and 3, longitudinal sections of the same, partially in side elevation, in locked and unlocked positions respectively, Fig. 4, a similar view of fastener with one member removed, Fig. 5, a side elevation of the removed member, Figs. 6 and 7, sections of the fastener on line 6—6 of Fig. 2, and 7—7 of Fig. 3 respectively, and Fig. 8, a section taken on line 8—8 of Fig. 4.

35 Like reference characters indicate like parts throughout the views.

The embodiment of my invention herein shown comprises a barrel or shell A composed of a cylindrical wall *a* closed at one 40 end; this closure is either integral with the wall *a* or, as shown, a frusto-conical shaped disk B engaged at its periphery by the beveled inner end face *b* of the swaged shell A. If preferred the member B may be soldered 45 in position rather than swaged; but the construction herein illustrated is much more advantageous. In the construction illustrated the end wall or disk B has an attaching member, projection, or eye *b'*.

50 Integral with or fixed by solder to an intermediate portion of the inner face of the wall *a* are two transversely curved longitudinally disposed shoulders or plates C, positioned diametrically opposite each other 55 with resultant spaces or channels *d* there-

between. Each member C is provided at its inner end midway its width with a longitudinal slot *e* extending a portion of the length of the plate C and forming segmental projections or ribs *f*. 60

Coöoperating with the described barrel member is a locking member G comprising a head *g*, slidably mounted in the shell *a*, and a shank *h*. In the present instance the end of the shank is rounded, as at *h'*. Near 65 its end the shank is provided at diametrically opposite points with lateral or radial lugs or projections *i* of such dimensions as to permit their passage through the openings or channels *d* and the slots *e*; and are 70 located at a sufficient distance from the head *g* to permit the free rotation of the member G without contact of the lugs with the fingers or shoulders *f* when the head abuts against plates C. The lugs are also so located 75 with relation to the depth of the slots *e* that when the former are seated in the latter the head *g* is flush with the open end of the barrel A.

The member G, in the construction illustrated has a projection, ring, or attaching member *j* upon the head *g*. 80

A plunger or block K is slidably mounted in the barrel, against one face of which presses one end of a spring L whose other 85 end abuts against the wall B. The spring is of such length that the block K is pressed against the end of the fingers *f* when the locking member is removed as shown in Fig. 4.

90 The operation of my device is as follows:— To engage the parts the member G is inserted into the barrel, the lugs *i* passing through the openings *d* until the head *g* abuts against the shoulders or plates C, and the spring L is compressed by the pressure of shank *h* against the block K. The relative positions of the parts at this stage being 95 shown in Figs. 3 and 7. The member G is then manually given a quarter turn, and the member K through the action of the spring L forces the member G outwardly until the lugs *i* seat themselves in the slots *e*, as shown in Figs. 2 and 6, thus locking the member G against rotation. The spring 100 pressed member K contacting with the end of the member *h* which preferably slightly projects beyond the fingers *f* prevents the accidental unseating of the lugs in a longitudinal direction. It will, therefore, be ob- 105 110

served that the engagement of the parts is certain, and the manipulation thereof facile.

Changes in details of construction within the spirit of my invention may be made, for 5 obvious modifications will occur to a person skilled in the art.

What I claim is:—

1. In a fastener, a barrel open at one end, 10 longitudinally disposed plates fixed within

said barrel and having longitudinal slots extending a portion of their length, a locking member slideable in said barrel and having radial lugs, and a plunger in said barrel engageable with the inner end of said locking member, said locking member having a head spaced from said lugs to be flush with the open end of the barrel when the locking member is at its outermost limit.

2. In a fastener, a barrel open at one end, 20 longitudinally disposed plates fixed within

said barrel and having longitudinal slots extending a portion of their length, a locking member slideable in said barrel and having radial lugs, and a plunger in said barrel

25 engageable with the inner end of said locking member, said locking member having a head spaced from said lugs to be flush with the open end of the barrel when the locking member is at its outermost limit, and a spring in the barrel forcing said plunger outward.

3. In a fastener, a barrel open at one end, 30 longitudinally disposed plates fixed within

said barrel and having longitudinal slots extending a portion of their length, a locking member slideable in said barrel and having radial lugs, a plunger in said barrel engageable with the inner end of said locking member, said locking member having a

40 head spaced from said lugs to be flush with the open end of the barrel when the locking member is at its outermost limit, and a spring in the barrel forcing said plunger outward, said locking member being rotatable in the barrel and having its inner end

45 extended beyond the inner ends of said

plates to engage said plunger when the locking member is at its outermost limit.

4. In a fastener, the combination with a 50 barrel provided with an open end, of internal longitudinally disposed plates spaced from each other on the barrel forming longitudinal passages, said plates being provided

with longitudinal slots in their ends opposite the open end of the barrel and diametrically opposite each other, an axially movable locking member comprising a head slidably mounted in the open end of the barrel,

a shank extending into the barrel, and lugs upon the shank diametrically opposite each 60 other adapted to enter the passages, and to register in the slots when the locking member is axially moved, and a member yieldingly mounted in the barrel engaging the shank, said locking member having a head 65

movable in the barrel and spaced from said lugs to be flush with the outer end of the barrel when the locking member is forced to its outermost position.

5. In a fastener, the combination with a 70 barrel provided with an open end, of oppositely disposed internal shoulders upon an intermediate portion of the barrel provided

with longitudinal slots forming seats, a rotatable locking member slidably mounted in 75 the open end of the barrel, radial lugs upon the locking member adapted to enter the slots, a plunger slidably mounted in the barrel in contact with the end of the locking member, and a spring in the barrel pressing 80

against the plunger, the locking member having its inner end extended beyond said shoulders and engaged with the said plunger when the said member is forced to its outermost position by said spring.

In testimony whereof I have affixed my signature in presence of two witnesses.

JOSEPH D. GILLAN.
